UNITED STATES PATENT OFFICE.

MERLE B. SHUTT, OF ALBUQUERQUE, NEW MEXICO.

LUBRICATOR-FILLER FOR STEAM-ENGINES.

1,217,846.

Specification of Letters Patent.

Patented Feb. 27, 1917.

Application filed September 22, 1916. Serial No. 121,587.

To all whom it may concern:

Be it known that I, MERLE B. SHUTT, a citizen of the United States, residing at Albuquerque, in the county of Bernalillo 5 and State of New Mexico, have invented certain new and useful Improvements in Lubricator-Fillers for Steam-Engines; and I do hereby declare the following to be a full, clear, and exact description of the invention, such as will enable others skilled in the art to which it appertains to make and use the same.

This invention relates to new and useful improvements in lubricator fillers for steam engines and the principal object of the invention is to provide a device which will enable the lubricator to be filled while the engine is running and without danger of loss of oil.

20 Another object of the invention is to provide a device which may be readily attached to an ordinary locomotive and which is so arranged that the oil will be forced into the lubricator against any slight pressure which 25 might have leaked thereinto from around the valves and pistons.

Heretofore considerable difficulty has been experienced in the filling of lubricators for the reason that the motion of the working parts of the engine has allowed certain portions of the steam to escape into the lubricator thereby forming a pressure which interferes with the filling of the same and causes a great waste of oil. This invention 35 will overcome this difficulty and enable the lubricator to be filled while the engine is in motion without any of the inconvenience usually required to fill the lubricator and without necessitating the engineer leaving 40 his seat.

With these and other objects in view the invention consists in the novel combination and arrangement of parts which will be fully set forth in the following specification 45 and accompanying drawing, in which:—

Figure 1 is a fragmentary sectional view of a locomotive showing this improved lubricator applied thereto, and

Fig. 2 is an enlarged view of the interior 50 of the lubricator.

Referring to the drawing the numeral 1 designates the boiler of the locomotive provided with the usual fire door 2 and having on the upper side of its rear end the tray 3 55 which usually supports the oil cans and the

like. The lubricator is designated by the numeral 4 and is located at any desired point on the engine as will be clearly seen upon reference to Fig. 1.

A filler is designated generally by the numeral 5 and comprises a tank 6 provided with the filling spout 7 which has a suitable cap 8 attached thereto in order to render the device air-tight. A suitable drain tap 9 is arranged near the bottom of the reservoir or 60 tank and is adapted to drain off the water which is fed thereto when the oil is being expelled therefrom. Leading into the tank to a point near the bottom thereof is the pipe 10 which leads to a pet cock 11 arranged to 65 enter the boiler at a point below the water line. It will thus be seen that when so desired water may be admitted from the boiler into the tank or receptacle 5 and when such water passes from the boiler it will be evident 70 that it will pass with considerable force due to the steam pressure within the boiler.

Leading from the tank or reservoir 5 is a lubricant conducting pipe 12 provided at its end with a pet cock 13 which is connected 80 by means of a nipple 14 to the lubricator 4. The pipe 12 extends into the reservoir 5 and terminates near the top thereof so that when the water is admitted from the boiler the oil will be forced upwardly and through the 85 pipe 12 into the lubricator.

In order to support the device in place on the tray 3 and avoid danger of the same becoming displaced, suitable lugs 15 are formed integrally with the reservoir 6 and 90 are provided with suitable openings for the reception of bolts which enter the boiler shell as clearly shown in Fig. 1. The height of the oil within the reservoir may be determined by a glance at the water glass 16 95 which is arranged in the side of the device and thus danger of admitting water to the lubricator is avoided.

It will be apparent from the foregoing that in use the reservoir 6 is first drained by 100 opening the pet cock 9 and it will be seen that upon closing said pet cock and opening the cap 8 the same may be filled with lubricant. When the train is in motion and it is desired to fill the lubricator the pet cocks 11 105 and 13 are opened and it will be seen that water flowing from the boiler through the pipe 10 will enter the reservoir 5 near the bottom and thus force the oil out through the pipe 12 into the lubricator. After the oil 110

has been entirely exhausted from the reservoir the pet cocks 11 and 13 are closed and it will be evident that further operation of the device will thus be prevented. The pet cock 9 may again be opened and it will be apparent that the water will be drained from the reservoir thus leaving the same ready for a second filling. Should it be desired to find out whether or not the entire amount of oil 10 has been exhausted from the reservoir, a glance at the glass 16 will inform the operator of the height of the oil and water within the reservoir.

While in the foregoing there has been shown and described the preferred embodiment of this invention, it is to be understood that such changes may be made in the combination and arrangement of parts as will fall within the spirit and scope of the 20 appended claim.

Copies of this patent may be obtained for five cents each, by addressing the "Commissioner of Patents, Washington, D. C."

What is claimed is:—

In a device of the class described the combination with a locomotive having a boiler and a lubricator, of a reservoir provided with a filling opening through which lubricant is adapted to be poured, an outlet pipe leading from the top of reservoir to the lubricator and a pressure inlet pipe extending through the top of the reservoir to a point near the bottom thereof and having its opposite end connected to the boiler below the water line, and valves for opening and closing the passages through the pipes. 25 30

In testimony whereof I affix my signature in presence of two witnesses.

MERLE B. SHUTT.
